UNITED STATES PATENT OFFICE.

SAMUEL FORRY LAUCKS AND WILLIAM E. WILKINSON, OF YORK, PENNSYLVANIA,
ASSIGNORS TO SAID LAUCKS.

METHOD OF CONSTRUCTING SAFES.

Application filed August 8, 1922. Serial No. 580,404.

This invention relates to a method of casting metals and specifically in some of its details to a method of casting linings, particularly linings of non-burnable metals in-
5 to receptacles, such as safes, vaults, etc.

It is a general object of the invention to provide an improved method of casting metals in an expeditious and inexpensive manner resulting in a superior product free from blow-holes or other defects.

Another object is the provision of an improved method for constructing safes, vaults or the like, which includes a novel method 15 of casting linings of non-burnable metal after the formation of the main body casting.

Other objects will be in part obvious in connection with the following detailed description and in part pointed out in connection 20 therewith.

The invention accordingly consists in the features of construction, combinations of elements and arrangement of parts which will be exemplified in the construction hereinafter set forth, and the scope of their application will appear in the appended claims 25

In the accompanying drawings wherein the application of the improved method is illustrated in connection with a safe construction,

Fig. 1 is a horizontal section through a safe constructed in accordance with the method of this invention;

Fig. 2 is an enlarged sectional view 35 through a door of a safe showing the method of applying a lining of non-burnable metal thereto;

Fig. 3 is a fragmentary sectional view similar to that of Fig. 1 but showing a modification; and

Fig. 4 shows a modified door construction.

Referring to the drawing for a detailed description of the illustrative methods of practicing this invention and first to Fig. 1, a main body casting or base 1 forming the external walls of a safe is shown.

This body casting is preferably of steel, usually manganese steel but some other metal may be used in its construction. The body casting 50 1 is formed to provide walls sur-

rounding an internal compartment, a door 2 opening through the front wall for providing access to the compartment. The interior lining 3 is of a non-burnable material, 55 having a high degree of conductivity, such,

for example, as copper, gray iron, etc., or an alloy of such metals. This non-burnable material resists the penetrating action of high temperature flames such as the oxy-acetylene torch, due to its high heat conducting properties dissipating the heat of the flames before the metal can reach the melting point. It is the placing of this lining in position in the body casting adjacent the walls of the interior compartment which 60 forms an important part of this invention.

The body casting having previously been formed by any approved method, a layer of non-metallic granular material 4, such as molding sand, ordinarily employed in the 65 casting process is placed against the walls of the inner compartment, the inner surfaces thereof being formed to correspond with the adjacent surfaces of the lining 3. A plurality of cores 5 of molding sand of the

proper size and dimensions are inserted through the doorway 2 into the inner compartment and are combined and arranged to fill the entire inner space with the exception of a shallow peripheral space corresponding in depth to the thickness of the lining 3 and lying between the cores 5 and the layer 4. This space is practically co-extensive with the inner surface presented by the layer 4 of molding sand but it may 70

extend therebeyond into appropriate recesses formed in the main body casting as indicated at 6 in Fig. 1. The inner cores 5 may also be arranged so as to provide a space for lining adjacent the inner face of the front wall next to the door opening. In this manner the lining space may be provided to overlie the entire inner surface of the compartment walls. Wax vents 7 will be suitably positioned in the core or layer 4 75

and similar vents may be employed in connection with cores 5, communicating with those of core 4 and leading to doorway 2. In the formation of these vents commercial wax is laid in the sand, as shown diagrammatically in an illustrative manner in Fig. 1, being positioned to provide ducts, when the wax is melted by baking the cores for leading away the gases incident to pouring the hot metal.

After the layer 4 is formed in position as disclosed the complete body casting including the layer 4 is heated substantially to a cherry red. The cores 5 are preferably made separately and baked separately and 100

105

After the layer 4 is formed in position as disclosed the complete body casting including the layer 4 is heated substantially to a cherry red. The cores 5 are preferably made separately and baked separately and 110

inserted into the casting compartment while the casting is still hot or the cores may be placed in position before the process of heating the body casting and the complete assembly can then be raised to the desired temperature. The heating as described results in freeing the casting and cores from moisture and other agencies detrimental to the perfect formation of the lining casting. 5 The cores may be provided with openings, (not shown) for pouring lining metal. The molten metal for the non-burnable lining is then poured while the assembly is still hot to completely fill the peripheral space provided for it and the whole is then allowed to cool off, the cores 5 being subsequently removed.

The employment of this method produces a lining free from blow-holes or other defects. It is clear that the method is as well adapted for placing linings of non-burnable or other material in old safes or vaults as for new construction. A burglar-proof or fire-proof safe is thus produced having a lining of non-burnable material placed in position to cooperate with the main body casting of the safe in effect providing compound walls therefor.

In the modification shown in Fig. 3 the 30 layer or core 4 of molding sand is omitted and the lining 3 is cast directly in contact with the inner faces of the compartment walls. The cores 5 are formed and placed in position as in the modification previously 35 set forth and the steps of heating the assembled parts and subsequently pouring the lining while the assembly is still hot are the same as previously described.

Fig. 2 shows a safe door construction in 40 which a non-burnable lining is cast in position in a cavity in the door in accordance with this invention. The body casting 10 of the door is preferably formed of manganese steel as in the case of the safe casting 45 1 previously described. The body casting of the door is formed with an interior cavity or compartment which may be partially filled with metallic slabs or plates 11 of different thicknesses arranged in layers and 50 designed to occupy any desired proportion of the inner compartment. Each layer of these plates is constructed in a plurality of sections so as to adapt them for ready insertion through the opening 12 in the inner 55 wall of the door. After these plates have been inserted in position to the desired degree, the lining 13 of non-burnable material is cast in position overlying the metallic plates, following the method outlined above 60 in connection with the placing of the lining 3. A core 14 of molding sand may be employed for this purpose and when placed in position the entire assembly is heated substantially to a cherry red, the lining 13 being 65 poured into the space provided for it while

the parts are still hot. The core 14 may also be heated before placing in position. If desired the door lining 13 may be constructed in hollow form, that is, in the form of a layer of non-burnable metal covering the inner walls of the door compartment. This is accomplished by placing molding cores in position within the door compartment in a manner similar to that disclosed above in connection with placing the lining 3 in Fig. 1.

In Fig. 4 a modified door construction is disclosed wherein the metallic plates 11 employed in Fig. 2 are omitted and the casting or lining 15 of non-burnable material fills the entire space of the door compartment. The method of heating the body casting and cores prior to pouring the lining is the same as described in the methods previously set forth.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention, which, as a matter of language, might be said to fall therebetween.

Having described our invention, what we claim as new and desire to secure by Letters Patent, is:

1. A method of forming safe structures or the like which includes, first forming a casting having a cavity therein, placing cores of molding sand within said casting so as to provide a space between the inner faces of said cores, heating the casting and cores and freeing the same from moisture and other injurious agencies and subsequently casting an inner lining of non-burnable metal in juxtaposition to a wall of said cavity while said casting is still hot whereby to provide a lining of high heat conductivity for said first-named casting.

2. A method of forming safe structures or the like, which includes the initial provision of a casting formed of a metal having properties offering high resistance to machining operations, applying a material of high heat resistant character to certain of the faces of said casting, said material being so applied as to provide channels extending through its body, filling said channels with material having a relatively low melting point, and subsequently casting a lining of a metal of high heat conductivity over said material.

3. A method of forming a safe structure, which includes utilizing a receptacle body of tool-resistant metal having an opening and a recess in its inner face adjacent such 5 opening, applying cores of heat-insulating, non-metallic material to the inner faces of said body, said cores being extended to a point adjacent said recess, heating the cores and body and thereupon casting a lining of 10 heat-dissipating metal to the inner faces of said cores and causing the said lining to extend into said recess.

4. A method of forming a safe structure, which includes providing a receptacle body 15 formed of tool-resistant metal and being provided with an opening, and a recess in its inner face and spaced from said opening, applying a layer of non-metallic, heat-resistant material to the inner faces of said 20 receptacle and to points adjacent the recess formed therein, and pouring a lining of heat-dissipating metal within said receptacle

and upon the inner face of said layer of material, said lining being caused to extend into said recess.

5. A method of forming a safe structure, which includes providing a receptacle of tool-resistant metal furnished with an opening and a recess in its inner face adjacent said opening, and casting a lining of heat- 30 dissipating metal within said receptacle body and extending into said recess.

6. A method of forming a safe structure, which includes providing a receptacle of tool-resistant metal formed with an opening, 35 and pouring into said body a lining of metal having heat-dissipating characteristics, said lining providing a receptacle within the body of the first and opening in the direction of the first receptacle opening. 40

In testimony whereof we affix our signatures.

SAMUEL FORRY LAUCKS.
WILLIAM E. WILKINSON.
